BEACH INSERTABLE STANDARD FOR PAIR OF FISHING POLES WITH FISH ALARMS

Augusta Tucker, Jr., 547 W. 91st St.,
Los Angeles, Calif. 90044

Filed Dec. 8, 1969, Ser. No. 20,395

Term of patent 14 years

Int. Cl. D22—05

U.S. Cl. D22—22

FIG. 1.

FIG. 2.

FIG. 3. FIG. 4.

FIG. 5.

FIG. 6.

FIG. 1 is a view in front elevation of a beach-insertable standard for a pair of fishing poles with fish alarms, showing my new design:

FIG. 2 is a rear view;

FIG. 3 is a side view;

FIG. 4 is a vertical sectional view taken on the line 4—4 of FIG. 1;

FIG. 5 is a plan view; and

FIG. 6 is a horizontal sectional view taken on the line 6—6 of FIG. 1.

I claim:

The ornamental design for a beach-insertable standard for a pair of fishing poles with fish alarms, substantially as shown.
